FOREIGN PATENT DOCUMENTS

WO 2017/209628 A1 12/2017

Primary Examiner — Anhdao Doan(74) *Attorney, Agent, or Firm* — Lee Sullivan Shea & Smith LLP(57) **CLAIM**

The ornamental design for a sampling apparatus, as shown and described.

DESCRIPTION

FIG. 1 is a side profile view of a sampling apparatus according to my new design, showing the swab head removed;

FIG. 2 is a perspective view thereof, showing the swab head removed;

FIG. 3 is a side profile view thereof, showing the swab head removed;

FIG. 4 is a top view thereof;

FIG. 5 is a bottom view thereof, showing the swab head attached;

FIG. 6 is a side profile view thereof, showing the swab head attached;

FIG. 7 is a perspective view thereof, showing an opened lid and showing the swab head attached; and,

FIG. 8 is a side profile view thereof, showing the swab head attached.

The broken lines illustrate portions of the sampling apparatus that form no part of the claimed design.
